UNITED STATES PATENT OFFICE.

JOSEPH HOLLINGSWORTH, OF JONESBOROUGH, INDIANA.

WASHING-MACHINE.

SPECIFICATION forming part of Letters Patent No. 292,314, dated January 22, 1884.

Application filed July 12, 1883. (No model.)

To all whom it may concern:

Be it known that I, JOSEPH HOLLINGSWORTH, a citizen of the United States, residing at Jonesborough, in the county of Grant and State of Indiana, have invented certain new and useful Improvements in Washing-Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a vertical sectional view of my machine, and Fig. 2 is a detail view.

This invention has relation to cylinders for steam washing-machines; and it consists in the 20 construction and novel arrangement of parts, as will be hereinafter fully described, and particularly pointed out in the claim appended.

Referring by letter to the accompanying drawings, *a* designates the steam-cylinder, constructed of the sections *b*, secured to the heads *c* in such a manner as to leave the spaces *e* between the sections *b*. The cylinder-heads *c* are further connected by rods or bars *f*, extending from head to head of the cylinder at 25 points directly opposite or in line with the spaces *e*, as shown. These rods or bars *f* are strengthened by short braces *g*, secured to the extensions *s* of the sections *b*, and to the rods or bars to hold them up under the weight of 30 the clothes. These rods or bars *f* are designed to hold the clothes up off from the walls of the cylinders and permit the steam and water in

the tank or boiler in which the cylinder is rotated to circulate freely through the clothes.

h designates the door in the cylinder-head 40 *c*, through which the clothes are introduced and removed.

i designates the hubs of the cylinder-heads, and *k* the journals for the cylinder, one of which is provided with a crank in the usual manner. 45 This cylinder may be cheaply constructed, is strong and durable, and performs its work in the most satisfactory manner.

The sections *b*, instead of being made angular, may be made in curved form, as shown in 50 Fig. 2, without departing from the character of my invention. I may therefore use either form of section in constructing my cylinder.

Having thus fully described my invention, what I claim as new, and desire to secure by 55 Letters Patent, is—

The combination, with the cylinder of a washing-machine constructed as described, and provided with the transverse openings *e*, 60 the walls *s* of which extend within the cylinder, of the bars *f*, connected at each end to the cylinder-heads, and with the said extensions by means of the brace-arms *g*, to hold the bars at a distance from the inner edges of the extensions, whereby a free passage is allowed for 65 the water and steam, and the clothes prevented from closing the said openings during operation.

In testimony whereof I affix my signature in presence of two witnesses.

JOSEPH HOLLINGSWORTH.
